UNITED STATES PATENT OFFICE.

ALBERT SNESRUD, OF WEBSTER, MINNESOTA.

TRIP FOR MANURE-CARRIERS.

1,355,860.

Specification of Letters Patent. Patented Oct. 19, 1920.

Application filed May 1, 1920. Serial No. 378,137.

To all whom it may concern:

Be it known that I, ALBERT SNESRUD, a citizen of the United States, residing at Webster, in the county of Rice and State 5 of Minnesota, have invented certain new and useful Improvements in Trips for Manure-Carriers; and I do hereby declare the following to be a full, clear, and exact description of the invention, such as will enable others skilled in the art to which it 10 pertains to make and use the same.

My invention has for its object to provide an extremely simple and efficient tripping device for manure carriers or like apparatus which includes a trolley arranged to run 15 on a wire or cable and having a dumping bucket.

The invention is illustrated in the accompanying drawings, wherein like characters 20 indicate like parts throughout the several views.

Referring to the drawings:

Figure 1 is a view in side elevation and some parts broken away, showing the tripping device applied to an elevated track cable and showing also the tripping plunger of the trolley; and

Fig. 2 is a section on the line 2—2 of Fig. 1.

30 The numeral 3 indicates an elevated track cable which may be a heavy wire, a rod, or woven wire cable and may be supported in the usual way.

The tripping device comprises a trip housing formed from sheet metal, bent into U-shaped form, as indicated by numeral 4. This housing straddles the cable 3 and hangs thereon like a saddle and, of course, is slidably adjustable thereon.

35 The numeral 5 indicates a frictional clamping dog that is pivoted at one end on a nut-equipped bolt 6 passed through the sides of the housing. This dog 6 is in the form of a quite stiff flat spring, the extended 40 arm of which has a depressed bulge 7. The numeral 8 indicates a clamping lever pivoted on a nut-equipped bolt 9 passed through the housing 4 and provided at its pivoted end with a cam lug 10 that is engageable 45 with the depressed portion 7 of the dog 6. The numeral 11 indicates a tripping lever pivotally hung at one end on the nut-equipped bolt 12 passed through the housing 4. The tripping lever 11 is bent on the 50 line of a compound curve, so that it will engage the clamping lever 8, as indicated by

broken dotted lines, when forced toward the right, in respect to Fig. 1.

The numeral 13 indicates the bucket tripping plunger of a trolley 14. Only a fragment of the trolley frame is shown, but it may be assumed to be of any one construction arranged to travel on the cable 3 in a well known manner and equipped with a dumping bucket adapted to be released by 60 depression of the tripping plunger 13. Normally, the tripping plunger 13 will stand at the elevation indicated by dotted lines 65 in Fig. 1.

The tripping device will be set on a cable 70 at any desired point and from time to time will be shifted so as to trip the bucket at the proper place.

When the tripping device is to be moved, the clamping lever 8 will be turned down 75 thereby releasing the frictional clamping dog 5 from the cable and permitting the housing 4 then to be slid freely on the cable.

To secure the housing into fixed position on the cable, the clamping lever 8 is forced 80 back upward to the position indicated in Fig. 1, thereby causing the cam lug 10 thereof to press against the bulge 7 of said dog, and this will press the dog 5 upward and cause the same to engage the under side of 85 the cable at two points, to wit, at points near the extremities of its bulged portion 7. The frictional clamping action thus produced on the cable by the top of the housing 4 and by the spring dog 6 will be sufficient to prevent 90 sliding of the housing 4 on the cable under the tripping act.

The tripping action produced is as follows:

When the bucket equipped trolley, with its 95 load, is moved outward or toward the right in respect to Fig. 1, its plunger 13, when it reaches the position marked *a* on Fig. 1, will engage the depending tripping lever 11 and will cause the same to swing toward the right and upward. When the tripping plunger 13 reaches the position marked *b* on Fig. 1, it will have carried the tripping lever 11 against the clamping lever 8, as indicated by broken lines in Fig. 1, and the 100 said tripping lever cannot be moved farther upward than said broken line position, because it is stopped by the clamping lever 8 and the clamping lever 8 is stopped against further upward movement by the engagement 105 of its free end with the cable 3.

When the trolley with its loaded bucket

is then moved farther toward the right, the tripping lever 11 will cam down or depress the tripping plunger 13, as indicated by full lines in Fig. 1, thereby tripping the bucket and permitting the same to drop its load. The trolley with its dump bucket will still move onward to the right until its depressed tripping plunger 13 has moved beyond the tripping lever 11 and has automatically then moved again upward to its normal position.

When the trolley and bucket are given their return movement toward the left, the tripping plunger 13 will engage the depending tripping lever 11 after it reaches the condition *b* in Fig. 1, and will cause the said lever to freely swing to the position indicated in dotted lines in Fig. 1; and when the said plunger 13 reaches its position *c* Fig. 1, it will pass from under the said lever 11 and permit the latter to again swing back to its depending position.

The tripping device above described is of small cost, hence may be quickly and easily operated and adjusted, and in practice has been found highly efficient for the purposes had in view.

What I claim is:

1. The combination with a cable, of a tripping device comprising a casing, embracing and mounted to slide thereon, a clamping dog applied within said casing and engageable with the under side of the cable, a clamping lever pivoted to said casing and having a lug working with a cam action against said dog, and a tripping lever pivoted to said casing, normally depending therefrom and arranged to be engaged with said clamping lever and thereby stopped in an operative position, said tripping lever being free to swing in opposite direction, to an inoperative position.

2. The combination with a cable, of a tripping device comprising a U-shaped casing, embracing and mounted to slide thereon, a spring-acting clamping dog applied within said casing and engageable with the under side of the cable, a clamping lever pivoted to said casing and having a lug working with a cam action against said dog, and a tripping lever pivoted to said casing, normally depending therefrom and arranged to be engaged with said clamping lever and thereby stopped in an operative position, said tripping lever being free to swing in opposite direction, to an inoperative position, the free end of said clamping lever being engageable with the under side of said cable to limit its movement in the direction in which it is pressed by an engagement therewith of said tripping lever.

3. The combination with a cable, of a tripping device comprising a U-shaped housing arranged to embrace and to slide upon said cable, a clamping dog pivotally connected to said housing at one end and having downwardly curved depressed portions, the extremities of which are engageable with the under side of said cable, a clamping lever pivoted to said housing and provided with a cam lug operative on the curved portion of said dog to press the same into engagement of said cable, the free end of said clamping lever being arranged to engage the under side of said cable to limit the movement thereof in its operative portion, and a longitudinally curved tripping lever pivoted to said housing at one end and normally depending therefrom but engageable with said clamping lever to limit its movement in one direction to an operative trip-actuating position.

In testimony whereof I affix my signature.
ALBERT SNESRUD.
